UNITED STATES PATENT OFFICE.

JOHN W. DOTY, OF OLNEY, ILLINOIS.

MOP.

Application filed July 5, 1927. Serial No. 203,478.

This invention relates to mops and more particularly to mops of the self-wringing type, the primary object of the invention being to provide a mop wherein both sides 5 of the mop strands may be used in mopping a surface.

Another object of the invention is to provide a mop frame including a handle and a frame movable with respect to the handle, 10 the frame being connected with the mop strands in such a way that by rotating the frame or the handle, the strands will be twisted to wring the mop.

A further object of the invention is to 15 provide means for securely fastening the inner ends of the mop strands to the mop head, thereby insuring against the strands becoming displaced while in use.

Still another object of the invention is 20 the provision of a mop frame constructed of twisted strands of wire, the ends of the wire frame being securely held to a block movable over the handle of the mop whereby the frame may be twisted to wring the 25 strands of the mop.

With the foregoing and other objects in view which will appear as the description proceeds, the invention resides in the combination and arrangement of parts and in 30 the details of construction hereinafter described and claimed, it being understood that changes in the precise embodiment of the invention herein disclosed, may be made within the scope of what is claimed, without departing from the spirit of the invention. 35

Referring to the drawings:

Figure 1 is a side elevational view illustrating a mop constructed in accordance with the invention.

Figure 2 is a plan view thereof.

Figure 3 is a longitudinal sectional view through the mop.

Figure 4 is a view illustrating the mop strands removed.

Figure 5 is a sectional view taken on line 5-5 of Figure 4.

Figure 6 is a view illustrating a modified form of the invention.

Figure 7 is a sectional view taken on line 7-7 of Figure 6.

Figure 8 is a sectional view taken on line 8-8 of Figure 6.

Referring to the drawings in detail, the mop includes a handle 5 to one end of which 55 is secured a bar 6, the bar 6 extending

transversely with respect to the handle 5 and supplied with socket members 7 to which the handle section 5 is bolted as by means of the bolt 8.

At the ends of the bar 6 are grooves 9 through which the side members 10 of the clamp 11 move, the clamp being in the form of a loop to cooperate with the bar 6 in clamping the free ends of the strands of the mop to the handle. The clamp 11 is 65 substantially rectangular in formation and includes a bar 12 that moves over the handle 5 when the clamp is moved into clamping relation with the mop strands.

The reference character 13 indicates a 70 pivoted latch member having a pin 14 extending downwardly therefrom, which pin is designed to frictionally engage the handle 5 to cause the latch member to be held in its active position, the pin acting as a stop 75 for the clamp to prevent the strands, which are indicated by the reference character 15 from being pulled from the clamp.

The mop frame includes a pair of arms 16 that have inwardly extended portions 17 terminating in parallel portions 18 that are pivotally connected to the block 19 by means of the screws 20, there being provided a metallic guard 21 positioned over one end of the block to partially cover the portions 80 18 of the frame, the member 21 being however spaced from the block to allow free movement of the frame with respect to the block, so that the frame may assume various 85 angles with respect to the block. 90

At the outer end of the frame is a rectangular member 22 that is supplied with a rod 23 extending throughout the length thereof and disposed intermediate the side bars of the member 22 so that the intermediate portions of the strands of the mop may be placed therearound, the free ends of the strands being brought into contact with the bar 6 and clamped in such position by means of the clamp 11. 95

From the foregoing it will be seen that the block 19 which is provided with a central opening through which the handle 5 moves, will set up a binding action with the handle to hold the frame in various 100 positions of adjustment.

It will also be seen that by moving the frame longitudinally of the handle and to a position to engage the free end of the latch member 13, the strands of the mop 110

will be stretched so that the full length of the mop head may be used for mopping a surface.

It will also be seen that both sides of the 5 mop strands may be used.

In the form of the invention indicated by Figure 6, the pivoted frame is formed by twisting wires upon each other as indicated at 24 and forming the wires into a loop, the 10 twisted wires at the outer end of the frame being separated as at 25. Secured to the frame adjacent to the outer end thereof is a wire 26 spaced from the portion 25 so that the strands of mop may be interwoven 15 therebetween to secure the mop strands to the frame.

The frame in this form of the invention also includes inwardly extended portions 27 and right angled end portions 28 that are 20 disposed in openings in the block 29 at opposite sides thereof, pivotally securing the frame to the block 29. Mounted on the block 29 is a wear plate 30 having openings registering with the openings of the block so that 25 the end members 28 may be passed therethrough.

In order that the right angled ends 28 may be held within the openings, metal 30 guards 31 are provided and disposed in spaced relation with the wear plates 30 defining a space to allow the frame to pivot with respect to the block 29. The handle 32 in this form of the invention also slides through the block 29 and is adapted to set 35 up a binding action between the handle and block when pressure is brought to bear on the frame of the mop in the act of mopping. It will also be seen that the block 29 may 40 be rotated with respect to the handle 32 twisting the mop strands to wring the mop.

I claim:

1. A mop including a handle, a clamp at

one end of the handle, a frame including a block and a body portion, said body portion being pivotally connected with the block, 45 said block being slidably mounted for movement longitudinally of the handle, mop strands connected with the outer end of the frame, said clamp adapted to secure the mop strands to the handle portion, and said mop strands adapted to be twisted to wring the mop, when the block and frame are rotated relative to the handle.

2. A mop including a handle, a frame embodying a block having an enlarged opening therein through which the handle extends, means pivotally connecting the frame to the block, means for restricting pivotal movement of the frame with respect to the block, mop strands secured to the frame and handle, said block being adapted to set up a binding action with the handle to restrict movement of the frame longitudinally of the handle when pressure is exerted on the mop in the act of mopping.

3. A mop including a handle, a block movable longitudinally of the handle, said block having lateral openings, a wire strand carrying frame having right angled extremities fitted in the openings to pivotally connect the frame and block, guard plates secured to the block and overlying the right angled ends of the frame, the sides of the guard plate being in spaced relation with the frame to permit of swinging movement 70 of the frame with respect to the block, and said block adapted to rotate relative to the handle to twist the mop strands to wring the mop.

In testimony that I claim the foregoing 80 as my own, I have hereto affixed my signature.

JOHN W. DOTY.
